RADIATOR VALVE.

Application filed May 16, 1923. Serial No. 639,230.

Our invention relates to improvements in radiator valves of the form that is used with steam radiators for controlling the vent opening to permit of the escape of air and to prevent the escape of the water of condensation and involving the use of a needle-valve in combination with an expansible element for the one result and in combination with a float for effecting the other, and the object of our improvement is to produce a radiator valve in which the expansible element and the float are virtually combined in a single structure, and which structure is provided with enclosing walls of relatively thin material, whereby a sensitive device is produced that operates substantially instantaneously responsive to changes in temperature, and, furthermore, which is provided with reinforcing means in the form of a spring for sustaining the walls under operative conditions and preventing collapse thereof.

In the accompanying drawing:

Figure 1 is a side elevation of our improved radiator valve.

Figure 2 is a plan view of the same.

Figure 3 is a sectional view on an enlarged scale on the line 3—3 of Fig. 2.

Figure 4 is a sectional view on the line 30 4—4 of Fig. 1.

Figure 5 is an end elevational view looking into the opening of the connecting nipple.

Figure 6 is a part sectional and part plan view of the adjusting member with an implement indicated as cooperating with the edge of the handle-disc for turning the same.

Figure 7 is a sectional view corresponding to Fig. 3 showing a modification of the adjusting means and adjacent parts.

Figure 8 is a fragmentary sectional view of a modification of the adjusting disc structure shown in Fig. 3.

Our improved radiator valve comprises a housing that is composed of a base part 10 and a cover part 11 extending upwardly therefrom, said base part having a laterally directed nipple 12 for connection with the radiator and said cover part 11 having a 45 perforation 13 in the top wall 14 that serves as the vent opening.

A drainage tube 15 may extend through

the nipple for draining the condensation within the valve structure into the radiator, as is common. In the present instance, however, the opening in the nipple is effectively divided by a transverse, horizontal bridge 55 16 into an upper part 17 and a lower part 18 and the drainage tube 15 is housed within the lower part 18.

The bridge 16 is actually located inwardly back of the entrance portion of the mouth of the nipple and is a diminutive structure, suited simply for retaining the drainage tube 15 in place.

The upper part 17 of the nipple opening serves also to provide means of access to the interior by means of a suitable implement of simple form for effecting changes in adjustment of the adjusting member 19 which is a screw-threaded structure, the changes being made by simply rotating the part to the extent desired.

Said adjusting member 19 is made of sheet metal and comprises a sleeve-like body part 75 20 that has an interior screw-thread for cooperating with an upwardly directed screw-threaded post 21 that is supported by the base part 10.

A plate or disc 22 extends outwardly radially from the body part 20 so as to be adapted to serve as a handle for manipulating the device. Said handle-disc 22 is located in registration with the upper part 17 of the nipple opening so as to be accessible for the purpose mentioned, permitting an implement to engage the periphery 23 thereof. Also, said periphery 23 may be of toothed form or roughened to facilitate the 80 85 adjusting operation.

The body part 20 terminates at the upper end 24 in the form of a generally V-shaped tip that serves as a support for the float 25 and to this end cooperates with a suitable concave structure or cup 26 in the bottom wall 27 thereof.

The float 25 is a hollow structure having a cylindrical side wall 28 that inter-connects the bottom wall 27 and the top wall 29.

The bottom wall 27 and top wall 29 are 100 dished or concave and may be provided adjacent the lateral edge each with a circular corrugation 30 to provide flexibility.

The upper wall 29 supports an upwardly

directed stem 31 that terminates at the upper end in the form of a tapered valve 32 that serves as a needle-valve in cooperation with a valve seat 33 at the lower end of the passage that serves as the vent opening 13.

The float 25 is hermetically sealed and contains a charge of simply air or a mixture of gases or a vapor. The walls thereof are made of sheet metal having a thickness of 10 only about five one-thousandths of an inch. The parts are generally adjusted to provide for a range of movement of about forty one-thousandths of an inch, such movement being effected either by expansion of the float 15 structure due to internal pressure or by flotation in condensation, as the case may be.

Under operating conditions there is always more or less tendency to collapse the walls of the float 25 and under certain extreme 20 conditions such tendency may be severe so as to be liable to be destructive. Wherefore, we find it expedient to provide a reinforcement for said walls and this in the present instance is in the form of a simple 25 spring 34 of generally U-shape and housed within the structure of the float, being made of a strip of flat material.

The ends of the spring 34 engage respectively with the top wall 29 and the bottom 30 wall 27. For positioning said spring 34 said ends are provided with suitable openings or slots in which are housed cooperating means in the form of a projection of one form or another.

35 Thus in the case of the top wall 29 the spring positioning means comprise a projection 35 in the form of a downward extension of the needle-valve stem 31 which passes through the upper end 36 of the spring 34 and is headed over at the lower end. In the case of the lower wall 27 that cooperates with the lower end 37 of the spring 34 the opening in the spring end 37 cooperates with the upper convex side of the 45 wall of the cup 26 that cooperates with the V-shaped tip 24 of the adjusting member 19.

The spring 34 is made of material that is about one-quarter of an inch wide and ten one-thousandths of an inch in thickness.

50 In the structure shown in Fig. 7 the float 25a has a bottom wall 27a that is provided with a downwardly directed pin or stem 38 that serves as the support therefor. Said pin 38 has a flange 48 that is seated upon the opposed upper end of a screw 39 that has screw-threaded engagement with the walls of an axially positioned chamber 40 that is provided in the base member 10a.

In the case of the form shown in Figs. 50 1 to 6 inclusive and having the adjusting member 19 there may be provided for convenience in assembling a plurality of seats 41 for temporarily supporting the float 25, there being, as shown, three such seats 41 distributed around the axially positioned tip

24. Also, as shown, said adjusting member 19 may be made of two parts that are united in any proper manner, said parts consisting of an axial member 49 that has at its lower end the sleeve-like body part or nipple part 20 and is projected through an opening in the other, radial member 42.

The radial member 42a shown in Fig. 8 is formed of a single piece of sheet metal that is cut and shaped suitably to provide the tip 24, the handle-disc 22, and the seats 41. The seats 41 are in the form of fingers that are formed by slitting the material of the disc-handle 22 inwardly from the periphery 23 and bending the free ends thereof upwardly.

The handle-disc 22 may be dished or concave on the under side for positioning the periphery 23 relatively to the upper part 17 of the opening in the side nipple 12. Said upper part or upper opening 17 serves as a window for admitting the adjusting implement, as has been described.

The single corrugation 30 in each case operates virtually as a hinge connection for the body portion of the bottom wall 27 and the top wall 29 that is enclosed by said corrugation. In changing from the depressed or inward position to the outer convex form and the reverse there is involved a snap movement, involving a preliminary buckling of the material, the spring operating to prevent such fluctuation and vibration as would otherwise follow responsive to relatively slight differences in temperature.

Considering the details of the top wall or roof 14 of the cover part 11, a depressed portion 43 is provided of annular form bordering the valve seat 33 that is connected with the side wall by means of an annular border portion 44 that has an arched or curved form of cross-section.

At the junction 45 of said depressed portion 43 and border portion 44 is a relatively sharply defined corner that serves as a dripping edge for shedding water of condensation.

Also, at the inner border of the depressed portion 43 is a corner 46 that acts in a similar manner, the last named corner 46 being provided at the junction with the upwardly directed conical structure 47 that terminates in the seat 33.

Means are thus provided for diverting water of condensation from the seat 33 and the vent opening 13, resulting in reducing the liability of plugging the outlet.

We claim as our invention:—

1. In a radiator valve, an upwardly directed body wall having a laterally directed nipple, a drainage tube located in the lower portion of the opening in said nipple and a bridge extending over the upper side of said tube, and said nipple opening comprising an upper portion that meets the interior

space that is enclosed by said body wall and serves to provide access to said interior space in a radial line above said bridge.

2. In combination in a radiator valve, a casing having a bottom wall and having a top wall that is provided with a vent opening, a float structure having a bottom for engaging with said bottom wall and a top that is provided with a valve for cooperating with said vent opening, and a spring 5 cooperating with said bottom and top.

3. In a radiator valve, an upwardly directed body wall having a laterally directed nipple, mechanism housed within said body 10 wall having means for adjustment, and said means being located so as to be accessible through said nipple.

4. In a radiator valve, a cylindrical casing having a top wall that is provided with a vent opening, an upwardly directed structure of conical form bordering said opening, an annular plain flat wall extending outwardly from the lower end of said structure, and a connecting wall intermediate said flat 25 wall and the outer wall of said casing that on the inside is of upwardly directed concave form of cross-section, whereby at the junction of said flat wall and connecting wall there will be provided a circular dripping edge that is relatively remote from the vent opening.

5. In a radiator valve, a casing having a vent opening in the upper wall and having in the interior a support that projects up-

wardly from the lower wall, a float having 35 a bottom and a top, said bottom making operative supporting contact with said support by its middle portion, a valve for cooperating with said opening projecting upwardly from the middle portion of said top, 40 said bottom and top being generally similar, made of sheet metal, and comprising for the major portion that extends outwardly from the middle portion a plain unbroken zone, and said bottom and top having adjacent the junction with the side wall in each case a single corrugation, whereby under conditions of use there will be reduced and substantially overcome the tendency for vibratory or fluctuating movement. 45

6. A radiator valve comprising a casing having a laterally directed nipple, moving mechanism housed within said casing and adapted to be manipulated to effect changes in adjustment, and said mechanism being positioned within said casing and relatively to said nipple so that changes in adjustment can be effected by means of an implement inserted through said nipple. 55

7. In a radiator valve, a casing enclosing moving parts, a top wall for said casing having a vent opening, and the portion of said top wall bordering said opening being of trough-like form so as to provide a receptacle for overflow of condensation. 60
